His Atty.

UNITED STATES PATENT OFFICE.

HENRY DREISOERNER, OF ST. LOUIS, MISSOURI.

PRIE-DIEU.

1,265,703.

Specification of Letters Patent.

Patented May 7, 1918.

Application filed February 14, 1916. Serial No. 78,227.

To all whom it may concern:

Be it known that I, HENRY DREISOERNER, a citizen of the United States, residing in the city of St. Louis and State of Missouri, have invented new and useful Improvements in Prie-Dieus, of which the following is a specification:

This invention relates to a novel article of furniture in the form of a priedieu, and has for its object to provide a device of this character which may be used either as a priedieu or as a seat, or in conjunction with other devices of the same character arranged in the manner of pews to serve both as a priedieu and seat.

The invention is illustrated in the accompanying drawing, in which—

Figure 1 is a view in front elevation of my improved device;

Fig. 2 is a cross sectional view of the same;

Fig. 3 is a view in rear elevation thereof; and

Fig. 4 represents, partly in elevation and partly in section, two of my improved devices arranged as pews, each device affording at one side a seat, and at its opposite or rear side a platform on which the worshiper may kneel.

Referring now to the drawing, the numerals 1, 2, indicate, respectively, the sides or side members of the priedieu, which are rigid and connected at their upper ends by a fixed top or rest 3, intermediate their ends by a cross bar 4, and toward their lower ends by similar cross bars 5. At a suitable distance below the top or rest 3 a shelf 6 is provided which extends between the sides 1 and 2, and is connected to said sides at its opposite ends, and below this shelf 6, and supporting the same, is an ornamental brace bar 7, which likewise is connected at its opposite ends to the sides 1 and 2. The numeral 8 indicates a seat which is pivotally mounted at 9 in the opposite side members 1 and 2, and when in the folded or raised position shown in Figs. 1, 2 and 3 it is in an inclined position between the elevated rest

3 and the kneeling support 15, its upper edge resting under the elevated rest and against the brace bar 7. Secured to the inner side of each of the side members 1 and 2 is a cleat 10, having a flat upper side 11, and an inclined rear side 11^a. With the seat in the raised position the under side of its rear edge portion engages the rear side 11^a of the cleats 10, and when the seat 8 is lowered its under side rests upon the tops of the cleats 10, as shown at the right of Fig. 4, and the rear portion of its upper side engages the bottom side of the cross bar 4, these parts serving to take the strain off of the pivots 9, when the seat is lowered, and to form a secure support for the seat. When the seat is raised the simultaneous engagement of its inner and outer edge portions with the cleats 10 and brace bar 7, respectively, serves to remove strain from the pivots 9. Secured on the inner side of each of the side members 1 and 2 toward the bottom thereof are two parallel guide bars 12, 13, the lower guide bar 13 being supported on the cross bars 5.

I provide suitable knee supporting means enabling a person to kneel at either side of the priedieu. This may be accomplished as follows: Slidably mounted between the respective guide bars 12, 13, is a slide in the form of two bars 14, which are connected at their opposite end portions, respectively, by supports 15, 16, which are of a width to afford sufficient surface for kneeling purposes. The support 16 has provided at its outer end legs 17 which are connected by a cross bar 18, which likewise serves to brace the support 16 on the under side. As will be understood from the above description, the bars 14, supports 15, 16, legs 17, and brace 18 form a unitary structure which is slidably mounted at opposite ends in the guide bars 12 and 13. The lower guide bars 13 are provided with stops 19, and the under side of the support 15 with pins 20 for engaging said stops to limit the outward movement of the bars 14 and supports 16, as indicated at the left of Fig. 4.

When used solely as a priedieu the seat 8

is turned upward to the position shown in Fig. 2, and the support 16 moved inward from the position shown at the left of Fig. 4 to that shown in Fig. 2, thereby bringing the support 15 in position to be knelt upon by the worshiper, who may use the top 3 as a rest for the hands, or the hands and head, when assuming the bowed position. When the seat is in this inclined position it 10 leaves the space between the kneeling support and the hand rest unobstructed so that the body of the kneeling person occupies the space normally occupied by the seat. The shelf 6 may be utilized for supporting hymn books, prayer books, and the like.

When used solely as a seat the supports 15 and 16 are left in the position shown in Fig. 2, and the seat 8 turned down to the position shown at the right of Fig. 4.

20 When my improved priedieus are arranged in the manner of pews, that is to say, one in front of the other, each forward priedieu has its support 16 pulled outward, as shown at the left of Fig. 4, so that the worshiper will use the seat 8 of the rear priedieu, and when kneeling the support 16 of the priedieu immediately in front of the one used for seating purposes.

The side members 1 and 2 have the general shape of the end of an ordinary pew, as 30 clearly illustrated in the drawing, and will be of any desired ornamental configuration.

The device as a whole may be manufactured at relatively small cost, and will be found exceedingly useful in small auditoriums, such as the chapels of cemeteries, or in temporary quarters used for worship, and where it is not desirable to install permanent seats.

40 I claim:

1. A priedieu having connected kneeling supports slidably mounted therein and movable into position for use, respectively, at either side of the device, and a seat pivotally mounted therein above said supports.

2. A priedieu comprising side members, each of which is provided on its inner side with guide bars, a support slidably mounted at opposite ends between said guide bars, 50 legs secured to said support, and a seat pivotally mounted in said priedieu above said support.

3. In a priedieu, in combination with side members having mounted thereon a kneeling-support, a seat pivotally mounted between said side members above said kneeling-support, a cleat secured on the inner side of each side member at the forward edge and affording supports on its upper and rear 60 side, a cross-bar connecting said side members and positioned to engage the upper side of the rear end portion of the seat when the latter is turned downward into contact

with said cleats, and a brace-bar extending between the side members and adapted to be 65 engaged by the outer edge of the seat at the same time that the under side of its rear edge portion engages the rear side of said cleats in the turned-up position of said seat.

4. In a priedieu, the combination of a 70 fixed elevated hand rest, a seat adjustable outwardly on one side of the priedieu, knee-supporting means constructed to form a knee support on the same side of the priedieu as said seat and adjustable outwardly 75 at the opposite side of the priedieu to support a person kneeling at the priedieu on the side opposite to the seat, means for supporting said seat in its outwardly adjusted position and in a folded position, said priedieu being unobstructed adjacent said kneeling support on the same side as said seat, whereby said seat when in said folded position leaves an unobstructed kneeling space on the same side of the priedieu as said seat. 80

5. In a priedieu, the combination of an elevated rest, a seat adjustable outwardly from the priedieu, means for supporting said seat in a substantially horizontal position, said priedieu having a kneeling support mounted to move toward and from opposite sides of the priedieu, said kneeling support having a part located toward the side of the priedieu remote from the seat to be knelt upon when the seat is in its horizontal position, said kneeling support having another part toward the same side of the priedieu as the seat to be knelt upon when the seat is in its folded position. 95

6. In a priedieu, the combination of an 100 elevated rest, a seat adjustable outwardly from the priedieu, means for supporting said seat in a substantially horizontal position, said priedieu having a kneeling support mounted to slide in a substantially horizontal direction near the floor, said kneeling support having a part located toward the side of the priedieu remote from the seat to be knelt upon when the seat is in its horizontal position, said kneeling support having another part toward the same side of the priedieu as the seat, to be knelt upon when the seat is in its folded position. 105

7. In a priedieu, the combination of a fixed elevated hand-rest, a seat adjustable 115 outwardly on one side of the priedieu, knee-supporting means including a slide constructed to form a knee support on the same side of the priedieu as said seat and adjustable outwardly to form a knee support at 120 the opposite side of the priedieu, to support a person kneeling at the priedieu on the side opposite to the seat, means for supporting said seat in its outwardly adjusted position and in a folded position, said 125 priedieu being unobstructed adjacent said

kneeling support on the same side as said seat, whereby said seat when in said folded position leaves an unobstructed kneeling space on the same side of the priedieu 5 as said seat.

8. In a priedieu, the combination of side members, an elevated rest, a seat adjustable outwardly at one side of said priedieu, relatively fixed means carried by said side 10 members for holding said seat in a substantially horizontal position and in a folded

position, and kneeling supporting means adjustable outwardly on the side of the priedieu opposite the seat to be used when the seat is not in its horizontal position, and 15 including a part adjustable outwardly on the same side of the priedieu with said seat to be knelt upon when the seat is in its folded position.

In testimony whereof, I have hereunto set 20 my hand.

HENRY DREISOERNER.
